UNITED STATES PATENT OFFICE.

FRANK J. BERNARD, OF PORTLAND, OREGON.

PLUMB BOB.

Application filed April 2, 1925. Serial No. 20,079.

My invention relates to plumb bobs in which the suspending cord enters the head axially, issues through a hole in the side of the neck, and is then wound around the neck 5 screw-fashion in one or more coils.

The objects of my invention are to furnish a plumb bob which will accurately center, which can be adjusted very precisely for height by the simple turning of the coils 10 around the neck, and which will retain its position on the cord without slipping.

Other objects and advantages are to be found in the construction and arrangement of parts, as will be described in the specification, and particularly pointed out in the appended claims.

I attain these objects with the mechanism illustrated in the accompanying drawing, in which—

20 Fig. I is an elevation of my plumb bob, the hole in the neck being shown in front.

Fig. II is a side view of Fig. I, the upper portion thereof being shown in section.

Fig. III is a rear view of the neck shown 25 in Fig. I.

Similar numerals refer to similar parts throughout the several views.

This plumb bob may be used for ordinary purposes but is especially valuable for high 30 class precision work, and has a tapering body portion 1 terminating downwardly in a removable steel point 2 to facilitate repair or exchange in case of accidental damage. The transverse hole 3 in the steel point 35 makes provisions for unscrewing the latter by means of a pin. The neck 4 of the plumb bob is comparatively long, cylindrical, and provided with a relatively large axial bore 5, which latter extends below a hole 6 entering the side of the neck 4 radially. The bushing 7 which is firmly inserted in the hole 6 should be of a length to extend a short distance to the outside of the neck and reach within one-half of the thickness of the cord 40 8 toward the center line of the axial bore 5. The head 9 of the plumb bob in the drawing is shown to consist of a plug which is screwed into the bore of the neck, but a screw cap could be equally well employed 45 providing the hole 10 in the head 9 is accurately proportioned to the diameter of the cord 8.

The plumb bob is now ready for the reception of the cord 8, the winding of which 50 latter is accomplished in the following manner: The lower of loose end of the cord 8 is

pressed against the neck 4 of the plumb bob with one hand. The upper part of the cord is then wound in one or more coils around the neck downwardly toward the body portion 1, as indicated by the numeral 11 in Fig. III, thereby clamping the loose end tightly between neck and coils in order to prevent the uncoiling of said loose end. Thereupon said upper part of the cord 8 65 is carried over the initial coils 11, as indicated by the numeral 12, and given several more turns upwardly toward the bushing 7. The upper terminal of the cord is then carried through the bushing 7 and finally 70 through the axial hole 10 in the head 9, the latter for this purpose being preferably unscrewed. The upper terminal of the cord can now be attached to the surveying instrument or any other support in the usual 75 manner.

To lengthen the cord of the suspended plumb bob, the coils around the neck are turned in a direction which will feed the coils of the cord into the bushing. The 80 shortening of the cord is accomplished by turning the coils in the opposite direction; in the latter case, however, the plumb bob should be slightly lifted in order to reduce the friction of the cord at both terminals of 85 the bushing.

It is truly surprising to experience the ease with which the length of the cord can thus be changed, how even small adjustments can effectively be accomplished, and 90 how firmly the plumb bob will retain its position without slipping, also the range of adjustment is considerable, as one or two coils of the cord around the neck suffice to retain the plumb bob in place, while the 95 neck is long enough to accommodate quite a number of coils.

The bore 5 in the neck is large enough to give easy access to the end of the cord as it protrudes from the inner end of the bushing during the insertion of the cord. The projection of the outer end of the bushing beyond the circumference of the neck has the purpose, partly to prevent the coils from encroaching upon the cord as it enters or 100 emerges from the bushing, and partly to form a guide whereby each newly formed coil is added in orderly array to the previously formed coils. Although the coils glide quite readily over the smooth surface 105 of the neck, it should, of course, be understood that the plumb bob itself must be pre-

vented from rotation when the cord is adjusted for length.

Having thus described my invention, it will be seen that my objects have been accomplished and, though I have shown the preferred form of construction, I reserve to myself the right to make minor changes, providing I do not contravene the spirit and principle of my invention.

10 I claim:

1. As an article of manufacture, a plumb bob having a tapering body portion, there being a removable steel point at the lower end of the body portion, a cylindrical neck 15 at the top of the body portion, said neck having a screw-threaded axial bore, a head screwably engaging said threaded bore, said head having an axial hole communicating with the axial bore in the neck, there being 20 a hole in the wall of the neck, and a bushing firmly mounted in the hole in the wall of the neck, said bushing projecting into the axial bore of the neck and beyond the outer circumference of said neck.
- 25 2. A plumb bob having a tapering body portion, there being a cylindrical neck at the top of the body portion, said neck having a screw-threaded axial bore, a head screwably engaging said threaded bore, said 30 head having an axial hole, there being a hole in the wall of the neck and a bushing traversing said hole in the wall of the neck in radial direction, with a cord coiled around the neck, the upper end of said cord enter-

ing the bushing and emerging through the 35 head.

3. A plumb bob having a tapering body portion, there being a cylindrical neck integrally with the body portion, a relatively large axial bore in the neck, a hole in the 40 wall of the neck, a head screwably engaging the neck, said head having an axial hole, a bushing traversing the hole in the wall of the neck in radial direction, with a cord coiled around the wall of the neck below the 45 bushing, the upper part of the cord entering the head and emerging at the side of the neck through the bushing, the inwardly projecting end of the bushing approaching the center line of the bore to within one-half 50 the diameter of the cord.

4. A plumb bob, having a tapering body portion, there being a cylindrical neck, an axial bore in the neck, a hole in the wall of the neck, a head screwably engaging the 55 neck, said head having an axial hole, a bushing traversing the hole in the wall of the neck in radial direction, said bushing communicating with the axial bore in the neck, with a cord coiled screw-fashion around the 60 neck, the lower end of the cord retaining its relative position to the coils by superimposing a part of said coils over said lower end of the cord.

Signed by me at Portland, Oregon, this 65
27th day of March, 1925.

FRANK J. BERNARD.
